BATTERY DISPLAY MERCHANTISER

Harry M. Channing, Wyomissing, Pa., assignor to General Battery Corporation, Reading, Pa., a corporation of New York

Original design application Dec. 19, 1968, Ser. No. 15,063, now Patent No. 217,941, dated June 30, 1970. Divided and this application Sept. 17, 1969, Ser. No. 19,821

Term of patent 14 years

Int. Cl. D6—01

U.S. Cl. D80—9

Fig. 1

Fig. 2

*Fig. 4**Fig. 3*

FIG. 1 is a perspective view of a battery display merchandiser embodying my new design;

FIG. 2 is a right side elevational view thereof;

FIG. 3 is a front elevational view thereof; and

FIG. 4 is a top plan view thereof.

This is a division of design application Ser. No. D.15,063, filed Dec. 19, 1968.

I claim:

The ornamental design for a battery display merchandiser, as shown.
